AUDIO TRANSMISSION CIRCUIT

Alda V. Bedford, Collingswood, N. J., assignor to
Radio Corporation of America, a corporation of
Delaware

Application August 22, 1942, Serial No. 455,734

4 Claims. (Cl. 179—1)

My present invention relates generally to sound transmission circuits and more particularly to a novel method of, and means for, transmitting audio waves from a sound wave source to a sound utilization circuit.

In radio broadcasting it is desirable to broadcast a program by a given station at a higher mean modulation level without overloading objectionably on the loud portions of the program. On the ordinary transmitter the level of transmission is not especially limited at the higher frequencies, but is limited uniformly at all frequencies by the condition representative of 100% modulation of the carrier. A signal having peak values in excess of that required to produce 100% modulation is sometimes applied to the transmitter to increase the transmitter range. However, when this is done the peaks of the audio signal are saturated off, thereby resulting in the generation, transmission and reception of harmonics of the audio frequencies. These harmonics are tremendously more objectionable than the mere limitation of loudness of the received sound.

If an ordinary limiting (or saturating) amplifier is used to limit the swing of extra loud portions of a program, it chops the waves so that new harmonics are produced, just the same as if the transmitter were limiting. Also, if the initial signal has components of two or more unharmonic frequencies, the conventional saturating amplifier will produce new components having frequencies equal to the sums and to the differences of the frequencies of the various original frequencies. These new components are particularly disagreeable to the listener, and make the use of a simple limiting amplifier unsatisfactory.

Accordingly, it may be stated to be one of the primary objects of my invention to provide a novel method of limiting, comprising dividing the original audio signal into a plurality of narrow audio bands, limiting the amplitude of the individual narrow bands, filtering the signal in each limited narrow audio band to remove substantially all spurious components, and then adding the several limited and filtered audio signals.

Another important object of my invention is to provide a novel method of sound transmission to a broadcast station which would allow a station of a given power to serve a greater population area, and to serve a given area with a more favorable signal-to-noise ratio.

Another object of this invention is to provide a novel method of transmitting audio signals which can be used with advantage to increase the signal-to-noise ratio for film or disc recording, 55

telephone communication or frequency modulation.

A more specific object of the invention is to provide the audio signal energy from a given source of audio waves into several frequency bands by means of band-pass filters, each of the bands representing slightly less than an octave, or a 2:1 range of frequencies, thereby permitting for some overlap of adjacent bands since the filters are limited as to the sharpness of cut-off; the signal energy in each narrow band being separately amplified by a saturating amplifier so as to limit any excessive peaks; and then passing the limiting energy of each band through another band-pass filter adapted to pass a similar frequency band thereby eliminating the harmonics generated by the saturating step.

The novel features which I believe to be characteristic of my invention are set forth in particularity in the appended claims; the invention itself, however, as to both its organization and method of operation will best be understood by reference to the following description taken in connection with the drawing in which I have indicated diagrammatically a circuit organization whereby my invention may be carried into effect.

In the drawing,

Fig. 1 schematically shows a system embodying the invention;

Fig. 2 illustrates the overlapping relation of the several audio band-pass filters used before and after the limiting amplifiers;

Fig. 3 shows a type of limiting amplifier that may be employed;

Fig. 4 graphically represents the effect of the present method in each narrow band.

In general, according to my invention, I divide the original audio signal energy into several narrow audio frequency bands by use of filters, and then limit the amplitude of the signal energy of each band separately by any desired type of limiting amplifier. Of course, new harmonics, as well as "sum and difference" frequencies, are generated by each limiter. However, in my system the output of each limiting amplifier is again filtered by a second band-pass filter to remove all spurious components. It is preferred that each band include only frequencies which are within a 2:1 range. This insures that all new spurious components, except those which are sums and/or differences of other sum and/or difference frequencies, are removed. That this is true can be determined readily by calculating various harmonics and the sum and difference frequencies which occur from various assumed

initial frequencies within a specific band such as from 162 to 290 cycles.

In this example, the lowest harmonic is double 162 which is 324, and the highest difference frequency obtainable is 128 cycles. These are outside the band. Of course the loud passages are made less loud by my method, but this is acceptable. The objectionable spurious frequencies usually associated with saturation are not heard. It is, also, pointed out that in the several bands given as examples herein, each represents slightly less than an octave. This is to allow for some overlap of adjacent bands, since the filters are limited in the sharpness of cut-off. If the saturating amplifiers are of the push-pull type, 15 or by other means are made symmetrical in their operation, each band may be made to include a frequency range of slightly less than 3:1, since only the second or higher harmonics are generated.

Referring, now, to Fig. 1 there is shown a system which embodies the invention. The various networks are schematically represented, since those skilled in the art are fully acquainted with the specific nature of the individual circuits which may be used. The source of audio waves 1 may be a microphone, a reproducer of a receiver, the electric pick-up of a record reproducer or a photocell pick-up device. In general, the numeral 1 may indicate some device which converts sound waves into audio frequency waves. By way of specific illustration, let it be assumed that source 1 is the microphone of a broadcast transmitter.

The audio waves are amplified by amplifier 2. 35 They are then applied to a plurality of band pass filters F_1 to F_9 , inclusive. The specific paths to filters F_5 to F_9 are omitted, but are suggested by dotted arrows. The filters F_1 to F_9 have respective pass band characteristics as indicated in Fig. 2. From this figure it will be noted that filter F_1 will pass audio signal energy of the narrow band of 50 to 90 cycles; F_2 passes 90-162 cycles; F_3 passes 162-290 cycles; F_4 passes 290-525 cycles; F_5 passes 525-945 cycles; F_6 passes 945-1700 cycles; F_7 passes 1700-3060 cycles; F_8 passes 3060-5500 cycles and F_9 passes 5500-9900 cycles. The band filters F_1 to F_9 are well known in the art. Each band represents slightly less than an octave, or a 2:1 range of frequency. This is to allow for some overlap of adjacent bands, since the filters are limited in the sharpness of cut-off. The response of each two adjacent filters in the overlap region is such that their sum is substantially 100% in order to provide a uniform overall response.

The output of each of filters F_1 to F_9 is passed through a respective limiting amplifier LA_1 to LA_9 , respectively. These limiting amplifiers may be of any well known form. The signal energy in each narrow band is separately amplified by a saturating, or limiting, amplifier so as to limit any excessive peaks. In Fig. 3 there is shown a well-known type of limiting amplifier which may be employed. This type of amplifier limits both the positive and negative swings, as illustrated at S_b in Fig. 4.

Referring specifically to Fig. 3, the input energy from a respective band is applied through condenser 5 to grid 6 of tube 1. The cathodes of tubes 1 and 8 are connected to the upper end of resistor 9. The grid 6 returns to the grounded end of cathode resistor 9 by a grid return resistor 10. The grid 11 of tube 8 returns to ground, and the plates of tubes 1 and 8 are con-

nected to the positive terminal of an energizing source. The limited audio voltage is taken off the plate end of plate resistor 12, and transmitted through coupling condenser 13 to the output circuit.

In operation, tube 1 limits the negative swing of the applied signal by the plate current going to zero, i. e., to cut-off. The cathode output of tube 1 is then applied to tube 8 by way of its cathode, the grid being grounded. The polarity of the cathode output of tube 1 is the same as that applied to its grid, but since this output is applied to the cathode of tube 8 instead of to its grid, the result is that tube 8 is in effect driven with the opposite polarity. Therefore, tube 8 limits the opposite side of the wave when it swings to plate current cut-off. This circuit is very advantageous as a limiter in that the clipping level for both tubes is fixed with respect to the alternating current axis of the original wave applied to tube 1. If the coupling between the two stages was not D. C. in character, the clipping level in the second tube would change with the shift in the alternating current axis caused by the clipping of only one side of the wave by tube 1.

The output voltage of each limiting amplifier is passed through a respective band pass filter. Thus, filters F_{10} to F_{30} may correspond in construction and characteristics to filters F_1 to F_9 respectively. These filters F_{10} to F_{30} remove any harmonics caused by the prior limiting action, as explained previously. The output energies of filters F_{10} to F_{30} are fed to mixer 3 where the energies are recombined or added to form a complete sound wave. After amplification at 4, the audio signal energy may be fed to the transmitter apparatus, or to a recording device, or may be transmitted over a line.

In Fig. 4 there is shown the effect of the present process on the audio wave. The figure is intended to apply to each narrow band only. The wave S_a represents the original wave. Limiting causes the flattening effect at S_b . The effect of F_{10} - F_{30} is to smooth the wave as at S_c . A slight amount of phase shift (not shown in the figure) may occur, but a reasonable phase shift in the filters would cause no harm. The loud passages are made less loud by this method, but that is acceptable. The objectionable spurious frequencies usually associated with saturation are not heard.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. A method of audio wave transmission which comprises dividing the audio wave energy into a plurality of narrow overlapping audio bands, 65 amplifying each narrow band and concurrently limiting such amplification, filtering each amplified narrow band to remove spurious frequencies caused by limiting action, and combining the filtered energies of the various bands to provide a wave having energy at all frequencies occurring in the original wave.

2. A method for limiting the amplitude of an original audio signal which consists in dividing the original audio signal into several narrow audio frequency bands, each band extending

slightly less than an octave, subjecting the audio energy of each narrow band to limiting amplification, removing any harmonics caused in each narrow band by said limiting amplification, and recombining the energies of the several narrow bands.

3. A method of transmitting a sound wave which includes converting the wave into audio signal energy, dividing the audio energy into a plurality of overlapping narrow bands of slightly less than an octave, limiting the amplitude of energy in each narrow band, and subjecting the limited energy of each narrow band to filtering to remove spurious frequencies caused by limiting

action, and combining the energies of the narrow bands to form the original audio signal wave.

4. A method of transmitting a sound wave which includes converting the wave into audio signal energy, dividing the audio energy into a plurality of overlapping narrow bands of slightly less than an octave, limiting the amplitude of energy in each narrow band, filtering the energy of each narrow band to remove spurious frequencies, and recombining the energies of all the bands to form the original signal whereby there is secured a reduction of peak amplitudes of the original wave relative to the average amplitude.
